US00D609077S

(12) **United States Design Patent**
Bucci

(10) **Patent No.:** **US D609,077 S**
(45) **Date of Patent:** **** Feb. 2, 2010**

(54) **DEVICE FOR SUPPORTING AN OBJECT**

(76) Inventor: **Michael Bucci**, 5720 Oak Mill Ct., Glen Allen, VA (US) 23059

(**) Term: **14 Years**

(21) Appl. No.: **29/343,675**

(22) Filed: **Sep. 17, 2009**

Related U.S. Application Data

(60) Division of application No. 29/334,086, filed on Mar. 20, 2009, now Pat. No. Des. 603,245, which is a continuation-in-part of application No. 29/326,489, filed on Oct. 20, 2008, now Pat. No. Des. 602,341, which is a continuation-in-part of application No. 29/283,426, filed on Aug. 14, 2007, now Pat. No. Des. 581,251, and a continuation-in-part of application No. 29/295,012, filed on Sep. 20, 2007, now Pat. No. Des. 581,254.

(57) **CLAIM**

I claim the ornamental design for a device for supporting an object, as shown and described.

DESCRIPTION

FIG. 1 is a perspective view of one embodiment of a device for supporting an object showing the new design;

FIG. 2 is a front elevational view thereof;

FIG. 3 is a rear elevational view thereof;

FIG. 4 is a top view thereof;

FIG. 5 is a bottom view thereof;

FIG. 6 is a perspective view of a second embodiment of a device for supporting an object;

FIG. 7 is a front elevational view thereof;

FIG. 8 is a rear elevational view thereof;

FIG. 9 is a top view thereof;

FIG. 10 is a bottom view thereof;

FIG. 11 is a perspective view of a third embodiment of a device for supporting an object;

FIG. 12 is a front elevational view thereof;

FIG. 13 is a right side elevational view thereof;

FIG. 14 is a rear elevational view thereof;

FIG. 15 is a left side elevational view thereof;

FIG. 16 is a top view thereof;

FIG. 17 is a bottom view thereof;

FIG. 18 is a perspective view of a fourth embodiment of a device for supporting an object;

FIG. 19 is a front elevational view thereof;

FIG. 20 is a right side elevational view thereof;

FIG. 21 is a rear elevational view thereof;

FIG. 22 is a left side elevational view thereof;

FIG. 23 is a top view thereof; and,

FIG. 24 is a bottom view thereof.
